UNITED STATES PATENT OFFICE.

MARTIN LANDENBERGER, JR., OF PHILADELPHIA, PENNSYLVANIA.

DESIGN FOR STOCKING FABRIC.

Specification forming part of Design No. 6,652, dated May 20, 1873; application filed May 6, 1873.

To all whom it may concern:

Be it known that I, MARTIN LANDENBERGER, Jr., of Philadelphia, Pennsylvania, have invented a Design for Stocking Fabric, of which the following is a specification:

The main peculiarity of my design, which is clearly illustrated by the figure in the accompanying drawing, is the stripe A, the edges of which are mottled, as shown, and blended into the body B of the fabric. The central portion of each stripe A is composed of three narrow parallel ribs of the character represented. The stripes A are alternated upon the body of the fabric with somewhat wider stripes D, each composed of a series of minor parallel

stripes, bars, or ribs, of different widths and shades or colors, arranged as shown.

Irrespective of the colors employed, I claim—

1. The design for the stripes A, substantially as shown and described.
2. The design for the whole pattern, including the stripes A and D.

In testimony whereof I have signed my name to this specification in the presence of two subscribing witnesses.

MARTIN LANDENBERGER, JR.
